SET OF PLAYING CARDS

Jacob Mass, Tel Aviv, Israel

Application January 6, 1955, Serial No. 33,852

Term of patent 7 years

(Cl. D34—13)

The single figure is a face view of a set of playing cards, showing my new design.

The cards are of no appreciable thickness, and the backs thereof are conventional in appearance.

I claim:

The ornamental design for a set of playing cards, as shown and described.
